(57) **CLAIM**

The ornamental design for a foot switch with mount, as shown and described.

DESCRIPTION

FIG. 1 is a left side view of a foot switch with mount illustrating the foot switch mount interacting with a pump; FIG. 2 is a front perspective view of the foot switch with mount;

FIG. 3 is a bottom view of the foot switch with mount; FIG. 4 is a top view of the foot switch with mount; FIG. 5 is a left side view of the foot switch with mount; FIG. 6 is a right side view of the foot switch with mount; FIG. 7 is a front elevation view of the foot switch with mount; and,

FIG. 8 is a rear elevation of the foot switch with mount. The broken lines shown in the drawings are for illustrative purposes only and forms no part of the claimed design.
